UNITED STATES PATENT OFFICE.

RUBEN HANDEL, OF COLUMBUS, OHIO.

VIOLIN HAND-SUPPORT.

1,271,460.

Specification of Letters Patent.

Patented July 2, 1918.

Application filed November 15, 1917. Serial No. 202,163.

To all whom it may concern:

Be it known that I, RUBEN HANDEL, a citizen of Russia, residing at Columbus, in the county of Franklin and State of Ohio, have invented certain new and useful Improvements in Violin Hand-Supports, of which the following is a specification.

This invention relates to musical instruments and has special reference to a violin 10 attachment designed to constitute a hand brace and support.

The principal object of the invention is to provide a new and improved device of this character interposed between the neck of 15 the violin and the hand of the player which will cause the player's hand to assume the correct and natural position for stopping the strings of such instrument while not interfering with the freedom of movement of 20 the hand.

In the accompanying drawing, like characters of reference indicate like parts in the several views, and:—

Figure 1 is a perspective view showing a 25 portion of a violin with the device in position thereon.

Fig. 2 is a detail perspective view of the device removed from the violin.

In carrying out the objects of this invention and in the form herein disclosed there is shown a clamp consisting of a cross bar 10 provided with a felted surface 11 arranged to engage beneath the lower or rear side of the body of a violin 12. Projecting 30 outward and upward from this cross bar are standards 13 whereon are screwed sleeve nuts 14 carrying at their upper ends rods 15 having inwardly projecting portions 16 arranged to support blocks 17 provided with 35 under surfaces of cork or felt as at 18. It is to be understood that the threads on the respective members 15 and 13 are of opposite hands so that rotating the sleeve nuts 14 causes the blocks 17 and cross piece 10 to 40 move toward or from each other thus permitting the clamp to be clamped firmly on the violin. Extending from the posts 13 are blocks 19 wherein fit the downturned arms 20 of a yoke 21, the blocks 19 being 45 provided if desired, with set screws 22 to hold said arms 20 in position. On the central portion of the yoke 21 and projecting therefrom under the neck of the violin is a threaded sleeve 23 wherein is screwed a 50 threaded stem 24 having on its end a circular 55

head 25 adapted to rest in the center of the user's hand as shown in Fig. 1.

In use the clamp is clamped on the violin and the yoke inserted in its proper position. The position of the head 25 is then adjusted 60 to hold the player's hand at the proper point, this being accomplished simply by rotating the head 25 and stem 24 so that the stem moves into or out of the sleeve 23 as desired. Then the player grasps the violin 65 in the usual manner with the head resting against his hand. It will be observed that this device is especially valuable in teaching the violin because it causes the player's hand to maintain the correct position. It is a 70 well known fact that there are several positions assumed by the player's hand in playing a violin, the different positions depending on the key in which the musical composition is to be played. This device insures the 75 correct position of the hand for the different keys as well as its correct position for fingering.

There has thus been provided a simple and efficient device of the kind described 80 and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, 90 what is claimed as new, is:—

1. A hand brace for violins, comprising a clamp provided with means for attachment to the body of a violin, a yoke, means for detachably connecting the yoke to the clamp 95 and an extensible hand brace carried by said yoke.

2. A hand brace for violins, comprising a clamp provided with means for attachment to a violin, blocks on said clamp, a yoke 100 provided with downturned ends engageable in said blocks, a threaded sleeve carried by the middle of said yoke and extending away from said clamp, a threaded stem screwed into said threaded sleeve and a head on said 105 threaded stem.

3. A hand brace for violins, comprising a clamp consisting of a cross bar, uprights at the ends of said cross bar, said cross bar being adapted to fit against the back of a 110

violin with the uprights lying adjacent the neck of the body, sleeve nuts threaded on said uprights, rods threaded into the upper end of said sleeve nuts, heads carried by said 5 rods and adapted to engage the front of the violin, blocks projecting from said uprights, a yoke having downturned ends engaged in said blocks, and an extensible arm carried by said yoke and arranged to lie beneath the

neck of the violin when the clamp is secured to said violin.

In testimony whereof I affix my signature in the presence of two witnesses.

RUBEN HANDEL.
